UNITED STATES PATENT OFFICE.

HANS BOSSART, OF LOS ANGELES, CALIFORNIA.

AEROPLANE

1,376,000.

Specification of Letters Patent. Patented Apr. 26, 1921.

Application filed February 16, 1918. Serial No. 217,579.

To all whom it may concern:

Be it known that I, HANS BOSSART, a citizen of the United States, residing at Los Angeles, in the county of Los Angeles and 5 State of California, have invented certain new and useful Improvements in Aeroplanes, of which the following is a specification.

This invention relates to air ships, of the 10 heavier than air type, and has for its object the production of a simple and efficient air ship which will maintain itself in the air, and will not be materially affected in its travel, by striking air holes or air pockets. 15 Another object of this invention is the production of a simple and efficient air ship wherein the supporting plane will be reinforced throughout its entire length, by means of the frame of the machine. 20 With these and other objects in view this invention consists of certain novel constructions, arrangement and combinations of parts as will be hereinafter fully described and claimed.

25 In the drawings:—

Figure 1 is a top plan view of the aeroplane,

Fig. 2 is a side elevation thereof,

Fig. 3 is a bottom plan of the aeroplane,

30 Fig. 4 is a section taken on line 4—4 of Fig. 1,

Fig. 5 is a section taken on line 5—5 of Fig. 1,

Fig. 6 is a section taken on line 6—6 of Fig. 1, through elevation rudder,

Fig. 7 is an enlarged transverse sectional view through a portion of a supporting plane.

By referring to the drawings, it will be 40 seen that 1 designates the supporting plane which is of a rectangular form having its longitudinal axis parallel to the course of flight. The supporting plane 1 is provided with curved rear portions 2 as shown in Fig. 1 of the drawings and this supporting plane 1 is provided with downwardly curved side edges 3, which are turned at quite an abrupt angle to the transverse axis of the plane, in this way producing an efficient air 45 receiving or engaging pocket upon the under face of the supporting plane 1. A frame 4 extends longitudinally through, or under the center of the plane 1 and elevation rudder 15. The frame 4 comprises top rails 5, bottom rails 10 and 6 and braces 7, 50 forming a rigid body preferably triangular

shape in cross section, with an enlarged compartment for the engine 9 and load adapted to be carried by the body.

The top rails 5 run parallel above the engine compartment and converge toward the forward and rear ends. The bottom rails 10 run parallel at the side of the engine compartment joining into one rail right in front and in rear of said compartment and 65 continue as one rail toward front and rear ends. The braces 7 connect the top and bottom rails.

The frame 4 terminates at the forward end thereof in an elevator rudder supporting frame 11, the frame 11 having an upwardly inclined forward lower face 12. The driving propeller shaft 13 is carried by elevator supporting frame 11 and a propeller blade 14 is carried by the shaft 13. 75

Elevator rudders 15 are pivotally mounted upon the frame 11 and each of these rudders is provided with a downwardly curved edge similar to the supporting plane 1. Each of the rudders 15 is mounted upon a 80 supporting shaft 16 and is adapted to be swung by means of operating wires or cables 17. A supporting member 18 is carried by the frame 4 and is provided with a guide 19 upon the upper end thereof 85 through which guide pass the upper tilting cables 20. The lower tilting cables 17 pass over guiding pulleys 21 and may be connected to a suitable operating means whereby the rudders 15 may be swung. 90

A direction rudder 22 is pivotally secured to the rear end of the frame 4 and is swung by means of the operating wires or cables 23, the cables 23 passing over the pulleys 24 carried by the plane 1. These wires or 95 cables 23 may be connected to the operating lever 25 for permitting the rudder 22 to be easily swung for the purpose of changing the direction of travel of the aeroplane.

The frame 4 tapers toward the bottom 100 thereof as the frame converges toward the rear of the plane 1, as indicated in section in Figs. 5 and 6 of the drawings. This frame 4 is provided with a widened face 26 located at a point constituting the engine receiving compartment and it should be understood that the load which is adapted to be carried by the aeroplane may be placed in the rear of the motor or engine 9, for the purpose of balancing the same. 105

The plane 1 may be formed of a frame work constituting a top plate 27 which is 110

braced by means of transversely extending ribs 28, a corrugated bracing means 29 being interposed between the brace 28 and the top plate 27. This top plate 27 is inclined upwardly toward the center thereof as shown clearly in Fig. 4 of the drawings.

If so desired the plane 1 may be formed of a frame work 30 which is braced by means of transversely extending braces 31 having downwardly extending ends 32. A corrugated bracing member 33 is interposed between the top of the frame 30, and the bracing means or members 31 as shown in Fig. 7. These braces 31 may be held in engagement with the frame 30 by means of securing clips 34. A suitable covering 35 may be placed upon the frame 30 as illustrated.

The planes themselves may be formed of tissue or aluminum sheets fastened underneath the side extension as shown in Fig. 7. The top plate or covering may be used to protect the frame from rain or snow.

From the foregoing description, it will be seen that a very simple and efficient aeroplane has been produced whereby the supporting plane is rectangular in shape and is mounted in such a manner as to extend longitudinally or parallel to the course of flight of the aeroplane. The frame 4 is secured only to the transversely extending bracing members 28 as indicated in Fig. 4, and as the aeroplane flies in a slightly inclined position, it should be understood that no considerable amount of air or current of air will pass over the top of the plane, and for this reason the ribs or braces 27 will not materially interfere with the passage of the aeroplane to the air. The aeroplane by being constructed as set forth, will offer a minimum amount of resistance to the air.

As shown in Fig. 6, the elevation rudders are braced by means of the transversely extending shaft 16.

By considering the drawings, it will be seen that the center of gravity is placed well below the supporting plane, and due to this fact, it will not be necessary to provide stabilizers for the machine. In view of the fact that a supporting plane is of considerably greater length than the width thereof, the sudden downward movement of the aeroplane, due to air holes, is not probable. It is preferable to have the supporting plane 1 of approximately two or three times longer than the width thereof.

Should it be desired to cause the aeroplane

to rise, the elevation rudders 15 may be tilted upwardly at their forward ends until the desired altitude has been reached, whereupon the elevation rudders may again be swung to cause the aeroplane to fly in a straight line, if it is desired to change the direction of travel laterally, the rudder 22 may be swung in the direction.

By turning the left hand elevation rudder (uppermost in Fig. 1) downwardly at its rear end, the aeroplane will incline on its longitudinal axis or toward one side thereof, and by similarly turning the right hand elevation rudder the aeroplane will fly upwardly and will prescribe a curve at approximately the same altitude. Then by turning the left hand elevation rudder upwardly again, the aeroplane will come back to its normal position and fly in a straight course when the right hand rudder has been adjusted and the steering rudder 22 has also been adjusted.

What is claimed is:—

1. An aeroplane of the class described having a frame comprising a pair of top rails, a pair of bottom rails converging at their front and rear ends into a single rail, braces for connecting said rails whereby said frame will be square in cross section intermediate its ends and triangular in cross section throughout its end portions, a plane situated on said frame, a rudder, and elevating means.

2. A frame for an aeroplane of the class described comprising a pair of top rails, a pair of bottom rails converging at their front and rear ends into a single rail, and braces for connecting said rails whereby said frame will be square in cross section intermediate its ends and triangular in cross section throughout its end portions.

3. A frame for an aeroplane of the class described comprising a pair of top rails, a pair of bottom rails converging at their front and rear ends into a single rail, said top rails being situated above said bottom rails and extending so as to run parallel with each other for a distance equal to the bottom rails and having their front and rear end portions converging, and braces for connecting said rails.

In testimony whereof I affix my signature in presence of two witnesses.

HANS BOSSART.
